UNITED STATES PATENT OFFICE.

HENRY HENKEN, OF SAVANNAH, GEORGIA.

STARTING DEVICE.

1,029,290.

Specification of Letters Patent. Patented June 11, 1912.

Application filed January 16, 1911. Serial No. 603,035.

To all whom it may concern:

Be it known that I, HENRY HENKEN, a citizen of the United States, residing at Savannah, in the county of Chatham and 5 State of Georgia, have invented certain new and useful Improvements in Starting Devices, of which the following is a specification.

This invention relates to starting devices 10 for hydrocarbon engines, being especially useful as a safety starting crank for such engines when employed as motors for automobiles and similar self-propelled vehicles. It is well known that a source of danger to 15 the operator resides in the means commonly employed in starting such engines, arising out of the fact that, owing to imperfect sparking or poor adjustment of the parts, the charge is sometimes ignited prematurely 20 relatively to the piston stroke, resulting in a reverse or backward movement of the engine shaft and of the starting crank, which latter is liable to injure the operator before it can be disengaged from the engine shaft. 25 To remedy this fault and eliminate the danger above mentioned, safety starting cranks have been heretofore proposed designed to disengage the starting crank from the engine shaft under a turning movement 30 of the latter in either direction; and the object of the present invention is to provide an improved and simplified mechanism of this class, which shall insure the certain separation of the starting crank from the engine 35 shaft under such a slight extent of backward movement of the latter as shall prevent danger of injury to the operator.

To this end my invention consists in a new and improved safety starting mechanism 40 substantially as hereinafter described and more particularly pointed out in the claims.

My invention, in an improved mechanical form, is illustrated in the accompanying drawing, wherein, Figure 1, represents a 45 view of the mechanism in side elevation and parts being broken away. Fig. 2, represents a vertical transverse sectional view on the plane indicated by the broken line 2—2, of Fig. 1. Fig. 3, represents a vertical transverse sectional view on the plane indicated by the broken line 1—1, Fig. 1, looking in the direction of the arrow 3, and Fig. 4, represents a view similar to that of Fig. 3, 50 on the same plane, but looking in the direction of the arrow 4.

Like reference characters mark the same

parts wherever they occur in the several figures of the drawing.

Referring specifically to the drawing, 5 designates one end portion of the engine 60 shaft shown as mounted in a suitable journal 6 formed on a portion of a supporting frame 7. To the end of the engine shaft is secured a clutch member in the form of a collar 8, on the outer face of which is an 65 annular series of clutch teeth 9. Rotatably mounted in journals 10 and 11 is the starting shaft 12, said shaft being disposed in endwise alinement with the engine shaft 5. On the inner end of the starting shaft 12 70 is loosely mounted a clutch member in the form of a collar 13, having on its inner end an annular series of clutch teeth 14, co-operating with clutch teeth 9, of the collar 8, and on its outer end, an annular series 75 of clutch teeth 15. Mounted on the starting shaft 12 is a collar 16 which is provided on its inner face with an annular series of clutch teeth 17, co-operating with the clutch teeth 15 on the inner face of the collar 13. 80 The starting shaft 12 is threaded at 18 and upon this thread is mounted a nut 19 between which, and the collar 16, an expanding spring 20 is coiled about the shaft 12. The spring 20 serves to normally and yield- 85 ingly press the collar 16 which is slidable, but not rotatable on the shaft 12, along said shaft inwardly, and to cause the teeth 17 to engage the teeth 15 of the collar 13, the collar 13 being mounted loosely, to both slide 90 and rotate freely on the starting shaft 12, and the collar 8, being rigidly secured on the engine shaft 5. The collar 16 is slidably keyed to the shaft 12 by the key 16' fitting in the groove 16'' of the crank shaft 12. 95 It will be observed that the positively acting faces of the teeth 15 and 17 are faced in the opposite direction, circumferentially of their respective collars, from the positively acting faces of the teeth 9 and 14, and that 100 the stress of the spring 20 will be increased by turning the nut 19 inwardly on the shaft 12 and correspondingly decreased by turning it outwardly thereon. A ratchet wheel or collar 21 is rigidly mounted upon the 105 shaft 12 and upon a suitable pivotal pin 22 is mounted a pawl 23 yieldingly held in contact with the ratchet wheel, by a suitable spring 24, Fig. 2, the teeth and pawl being arranged to permit of the forward rotation 110 of the shaft 12, to the right, by means of a suitable crank 25 secured upon its outer end,

but to prevent the backward rotation, to the left, in a well known manner.

When the engine is to be started, the starting shaft is pressed inward to engage teeth 9 and 14 and bring the parts to the positions indicated in Fig. 1, when the crank 25 is turned to the right, and the nut 19 having been turned inwardly far enough to so increase the tension to an extent to cause collars 16 and 13 to turn with each other the engine shaft is turned, or cranked in the usual manner. After the engine has been started in a forwardly direction, the teeth 9 of the collar 8 will overrun teeth 14 of collar 13, forcing the starting device to slide away in a longitudinal direction, thus disconnecting same from the engine in the usual well known manner, the nut 26 preventing longitudinal inward displacement 20 of the collar 13 with relation to the crank shaft. Should the engine "back fire" during the cranking operation, and the shaft start to rotate backward, the teeth 15 will slide over teeth 17 with sufficient force to 25 slide collar 16 outward on shaft 12, overcoming the tension of spring 20 and thus permit the operator to retain his hold on the crank and thus avoid injury to himself, or to the machine, by the rapid backward rotation of shaft 12 which would otherwise occur.

It will be observed that the rotation of the cranking shaft is yieldingly transmitted to the engine shaft so that the rotation of the latter will not be communicated to the former in the event of extraordinary resistance due to breakage or wrong adjustment of parts thus avoiding another source of trouble. The teeth 14 and 9 between collars 13 and 8 will slip with less resistance than the teeth 15 of collars 13 and 16 so that the overrunning forwardly of the engine shaft will be easy, and not tend too strongly to carry the cranking shaft with it. The inclination of the teeth 15 and 17 on collars 13 and 16 is more abrupt, and the resistance they offer, due to the springs 20, to sliding over each other, is sufficient to rotate the engine shaft 5 under all ordinary 50 circumstances, while they may slip over each other to avoid accident.

To provide means whereby endwise movement of the starting shaft is permitted, the width of the ratchet wheel or collar 21 is 55 made less than the distance between the bearings 10 and 11, as shown in Fig. 1. The collar 13, is limited in its inward movement on the starting shaft under the stress of spring 20, by a nut 26 on the threaded 60 inner end of the starting shaft 12, so that when the starting shaft is in its normal outward position, in which the ratchet wheel or drum 21 will be in contact with the journal plate 11, the teeth 14 of collar 13 will 65 be out of contact with the teeth 9 of collar

8 during the rotation of shaft 5 in running the machine.

While I have described specifically the parts of the embodiment of my invention herein illustrated, it will be obvious to those familiar with the art, that many changes and variations may be made in the construction of the several parts, without departing from the spirit and scope of the invention.

Having thus fully described my invention, what I claim as new and desire to secure by Letters Patent of the United States is:

1. In a cranking device for engines, the combination with an engine shaft having a clutch collar rigidly secured thereon, of a cranking shaft in alinement with the engine shaft, a double-ended clutch member loosely mounted on the cranking shaft and adapted to have its clutch teeth at its inner end engage with the clutch teeth of the clutch collar on the engine shaft, a clutch collar slidably mounted on the cranking shaft in advance of said double-ended clutch member with the clutching teeth of the last mentioned clutch collar being adapted to engage the clutch teeth at the outer end of the double-ended clutch member, the teeth at the outer end of said clutch member being disposed on a plane opposite to the plane of the clutching teeth at the inner end of the double-ended clutch member with the teeth of the clutch collar of the engine shaft and the teeth of the clutch collar of the cranking shaft being correspondingly formed for coöperation with the clutching teeth of the double-ended clutch member and with the clutch teeth at the outer end of the double-ended clutch member formed more abrupt than the teeth at the inner end of the clutch member, a nut on the cranking shaft in alinement with said clutch member and clutch collars, and a spring coiled around the cranking shaft between said nut and the outer end of the clutch collar of the cranking shaft to hold the latter clutch collar and the double-ended clutch member in coöperative relation, whereby the cranking shaft may be rotated to start the engine shaft and whereby in the event of back firing of the engine shaft when rotating the latter to start the engine the teeth at the outer end of the double-ended clutch member will ride over the teeth of the clutch collar on the cranking shaft.

2. In a cranking device for engines, the combination with an engine shaft having a clutch collar rigidly secured thereon, of a cranking shaft in alinement with the engine shaft, a double-ended clutch member slidably and rotatably mounted on the cranking shaft with the teeth at its inner end adapted to engage the teeth of the clutch collar on the engine shaft, a clutch collar slidably mounted on the cranking shaft in front of the double-ended clutch

- member and having its teeth formed to co-operate with the teeth at the outer end of the double-ended clutch member, means for yieldably holding the double-ended clutch member and the clutch collar of the cranking shaft in coöperative relation, the inner end of the cranking shaft being reduced or its reduced portion screw threaded and a nut secured to the reduced, screw threaded inner end of the cranking shaft to form a stop to limit the sliding movement of the double-ended clutch member inwardly of the cranking shaft when the latter is in its normal position.
- 15 3. In a cranking device for engines, the combination with the engine shaft and a clutch collar rigidly secured thereon, of a cranking shaft in alinement with the engine shaft, a clutch collar loosely mounted on the cranking shaft adapted to engage with the clutch collar on the engine shaft, a third clutch collar slidably mounted on the cranking shaft and adapted to engage the loose clutch collar, a nut threaded on the cranking shaft, a spring coiled around the cranking shaft between the nut and the slidable clutch collar, two bearings for the cranking shaft, and ratchet mechanism comprising a ratchet collar on the shaft between said bearings of less length than the distance between said bearings and means whereby the cranking shaft may be rotated.
- 20 In testimony whereof I affix my signature in presence of two witnesses.
- 25 HENRY HENKEN.
